(57) **CLAIM**

The ornamental design for a grab bar for vehicle, as shown and described.

DESCRIPTION

FIG. 1 is a perspective view of a grab bar for vehicle showing my new design.

FIG. 2 is a front view thereof.

FIG. 3 is a rear view thereof.

FIG. 4 is a left side view thereof.

FIG. 5 is a right side view thereof.

FIG. 6 is a top view thereof shown in enlarged scale; and, FIG. 7 is a bottom view thereof.

The broken lines shown herein are for the purpose of illustrating portions of the grab bar for vehicle and form no part of the claimed design.
